WINDOW CLEANING DEVICE

Frederick Supnick, Brooklyn, N. Y., assignor of
one-half to Rose Saxe, Brooklyn, N. Y.

Application May 31, 1941, Serial No. 395,913

10 Claims. (Cl. 15—251)

This invention relates to new and useful improvements in a window cleaning device.

The invention proposes the construction of a device as mentioned which is of particularly simple construction, light weight, labor saving, and which may be conveniently manipulated from inside a window to effectively clean the outside. Thus the device is in the nature of a safety device because the necessity of sitting out on a window or bending out has been eliminated.

It is proposed to characterize the window cleaning device by a carriage adapted to rest upon and move laterally along the sill of the window, and by a light-weight frame slidably mounted on the carriage to be manually moved inwards and outwards of the window. Furthermore, it is proposed to mount an arm which is provided with a window cleaning member, on the outer end of the frame in such a manner that it resiliently engages against the outside of the window during the manipulation of the frame.

Another object of the invention resides in the provision of means by which the window cleaning member and arm may be moved slightly outwards to engage over the separating strips in certain windows during the cleaning thereof.

The invention particularly proposes to construct the arm which supports the window cleaning member of flexible material, and to supplement this flexible construction with resilient means acting in conjunction with the arm for resiliently urging the arm towards the window. With this arrangement the window cleaning member will always maintain contact with the outside of the window when the frame is moved inwards and outwards.

Another object of the invention resides in constructing the window cleaning member in a certain way to more effectively clean the window during the operation of the device. A construction is further proposed by which cleaning cloths, or other sheets of material may be effectively clamped upon and removed from a support of the cleaning member, as desired.

Another object of the invention resides in constructing the said carriage which rests upon and moves laterally on the window sill in a certain way that it may readily be adapted to window sills of different designs.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a fragmentary vertical sectional view of a window equipped with a window cleaning device which is viewed in elevation.

Fig. 2 is a fragmentary horizontal sectional view taken on the line 2—2 of Fig. 1.

Fig. 3 is a fragmentary enlarged vertical sectional view taken on the line 3—3 of Fig. 2.

Fig. 4 is a fragmentary enlarged sectional view taken on the line 4—4 of Fig. 1.

Fig. 5 is a fragmentary enlarged vertical sectional view taken on the line 5—5 of Fig. 2.

Fig. 6 is a fragmentary enlarged vertical sectional view taken on the line 6—6 of Fig. 2.

Fig. 7 is a fragmentary elevational view looking in the direction of the line 7—7 of Fig. 1.

Fig. 8 is a fragmentary enlarged elevational view looking in the direction of the line 8—8 of Fig. 1.

Fig. 9 is a vertical sectional view taken on the line 9—9 of Fig. 8.

Fig. 10 is a fragmentary enlarged detailed view of a portion of Fig. 2 to more clearly illustrate certain of the parts.

The window cleaning device, in accordance with this invention, is intended to clean windows, as for example the window 12, which has a sill 13 or other bottom support. The window 12 also has the usual outer sash 14 and inner sash 15. The window cleaning device includes a carriage 16 adapted to rest upon and be moved laterally on the said window sill 13. A frame 17 is slidably mounted on the carriage 16 and is adapted to be manually moved inwards and outwards of said window sill 13. An arm 18 is mounted on the outer end of the frame 17. A window cleaning member 19 is mounted on the outer end of the arm 18 and is adapted to engage against the outer face of the window panes of the window 12. Means is provided for resiliently urging the arm 18 towards the said window 12, for urging the member 19 against the panes of the window during the inward and outward motion of the frame 17 during the use of the window cleaning device.

The carriage 16 includes an inner body section 16' and an outer body section 16''. The inner body section 16' comprises a pair of inverted L-shaped strips 20 spaced from each other and fixedly held by a transverse strip 21. Rollers 22 are mounted upon the ends of the transverse strip 21. A socket 23 is mounted on the top of each strip 20. The outer body section 16'' includes a pair of strips 24 slidably engaged through the sockets 23. A transverse strip 25 is

mounted across the outer ends of the strips 24. Rollers 22 are mounted upon the ends of the transverse strip 25. Each socket 23 is provided with a clamp screw 26 by which the strips 24 may be fixedly held. The arrangement is such that the clamp screws 26 may be loosened and then the body section 16' and 16'' shifted towards or away from each other to adjust the width of the carriage 16 so that it may properly engage the window sill 13.

Each roller 22 is provided with a cylindrical body portion 28 and a flange 29. Cushioning material, such as rubber sheet material 30 is mounted upon each roller at points to engage the window sill and prevent damage to the sill during the operation of the device. Each roller 22 is rotatively mounted on a stud 31 which is mounted upon said transverse strips 21 and 25. The tops of the sections 16' and 16'' are disposed at a slant so as to slope downwards and outwards. This facilitates holding the frame 17 in a similar position, as illustrated in Fig. 1. The flanges 29 of the rollers 22 are adapted to engage edge portions or shoulder portions normally formed on window sills, as for example clearly shown in Fig. 1. Hooks 21a are also mounted on the transverse strips 21 and extend downwards to the inside of the window sill 13 for preventing accidental outward falling off of the carriage 16 from the window sill.

The frame 17 includes a rigid strip 32 extending longitudinally of the carriage 16 and having its inner end formed with a handle 33 by which the frame may be conveniently gripped. The frame 17 also includes a crossbar 34 mounted across an inner end portion of the strip 32 and another crossbar 35 mounted across the outer end of the strip 32. This outer crossbar 35 has its end portions 36 bent upwards at right angles to the main portion thereof. Tracks 37 are mounted on the said crossbars 34 and 35 and extend parallel to the strip 32. These tracks 37 are in the form of tightly stretched rods or wires. Each rod or wire 37 has one of its end portions stationarily mounted on the cross piece 34 by being looped through an opening 38 formed in the cross piece. A holding member 39 holds the end portion of each loop in the loop formation. The other end of each rod or wire 37 is formed into a loop portion which is held by a similar member 39. However, this latter loop portion engages upon a hook 40 which is adjustably mounted upon the cross bar 35.

More specifically, a socket 41 is provided for each hook 40 and is fixedly mounted on the cross piece 35. The hook 40 slidably engages through the socket 41. A pin 42 is mounted on the socket 41 and engages a slot 43 formed in the side of the arm of the hook 40 to prevent it from turning. Thus the hook 40 may only move inwards and outwards. A wing nut 44 is threadedly engaged upon the shank portion of the hook 40 and abuts the end of the socket 41. With this arrangement the nut 44 may be turned to move the hook 40 so as to stretch the rod or wire 37 for holding it in its tautly stretched condition.

The tracks 37 are engaged upon guides 45 mounted on the carriage 16. These guides 45 are in the form of blocks 46 mounted upon the strips 24 of the carriage 16 and each block 46 is provided with a slot 47 for receiving the track, or wire 37. Springs 48 are mounted in the slots 47 and act to normally hold the tracks 37 from accidentally disconnecting from the guides 45.

However, when it is desired to disconnect the frame 17 from the carriage 16, these parts may be relatively moved and then the tracks 37 will be forced out between the springs 48. Auxiliary guides 49 are mounted on the strips 24, inwards of the guides 45 and are adapted to assist in guiding the tracks 37. These auxiliary guides 49 comprise vertical members 50 mounted on the strips 24 and carrying tubular protectors 51 preferably made from heavy cloth material and against which the tracks 37 engage.

A bar 52 for limiting downward motion of the frame 17 is mounted across the inner ends of the strips 24. The bottom edge portion of the window sash being cleaned serves as a limiting means for preventing excessive upward motion of the frame 17. The arrangement is such that the handle 33 may be gripped and the frame 17 reciprocated inwards and outwards, and during this reciprocation it will be held against lateral movement by the guides 45 and the auxiliary guides 49. A flexible protector 90 is attached to the transverse strip 25 and depends outwards over and down the window sill 13. The protector 90 comprises several flexible strands 90a supporting a plurality of closely spaced wooden rods 90b. The protector 90 prevents injury to the frame 17 and tracks 37 during the operation of the window cleaning device.

The arm 18 preferably comprises a flexible stem 53 which is connected with a bracket 54 at its bottom end. This bracket 54 has down-turned end portions 55 which are disposed adjacent the upturned end portions 36 of the crossbar 35. Pintles 56 pivotally connect these adjacent end portions. The construction is such that the flexible stem 53 may pivot upwards and downwards on the pintles 56. A yoke 57 is mounted on the top end of the flexible stem 53 and is provided with a pair of outwardly disposed ends 58. The window cleaning member 19 includes a flat plate 59 having socket portions 60 located above its horizontal center to make the window cleaning member 19 bottom heavy and said sockets 60 receiving the outwardly disposed ends 58 so that the window cleaning member 19 is pivotally mounted on the yoke 57, and due to the action of gravity seek a vertical position.

The side arms of the yoke 57 may be pressed together to disengage the outwardly disposed ends 58 from the sockets 60 and then the window cleaning member 19 may be removed from the arm 18. The window cleaning member 19 also includes a sheet of covering material 61 such as a cleaning cloth, or a sheet of chamois or other similar material. This sheet 61 has several rubber strips 62a fixedly mounted upon its inner face in positions to rest against the plate 59. These strips 62a are adapted to more effectively press portions of the sheet 61 against the window being cleaned so as to increase the pressure per square inch of the operative parts of the sheet 61 and thus more effectively carry out the cleaning operation. The sheet 61 is removably supported on the flat plate 59 by several clamps 62 and 62' mounted along the edges of the plate 59. These clamps 62 and 62' are adapted to grip the edge portions of the sheet 61. Each clamp 62 includes a jaw 63 pivotally mounted on a rod 64 supported upon the plate 59 by the lugs 65. A spring 66 is mounted on the rod 64 and acts between the plate 59 and jaw 63 for urging the jaw 63 into gripping position. The clamp 62' includes a jaw 63' pivotally mounted on a rod 64' supported by lugs 65' on the plate

59. A spring 66 is mounted on the rod 64' and acts between the plate 59 and jaw 63' for urging the jaw 63' closed. The major portion of the clamp 62' is within the arms of the yoke 57.

Means is also provided, as previously stated, for resiliently urging the arm 18 towards the window 12 for urging the member 19 against the window during the inward and outward motion of the frame 17. This means includes a slide 67 mounted upon the stem 53 and provided with a pair of lug portions 68 which are connected with springs 69. These springs 69 extend downwards and are hooked upon a plate 70 which is fixedly mounted upon the outer end of the strip 32 of the frame 17. The slide 67 is fixedly held in adjusted positions. The means for accomplishing this includes a screw 71 rotatively mounted through a lug 72 on the stem 53. This screw 71 threadedly engages a lug 73 on the slide 67. The screw 71 has a head 74 by which it may be turned. The arrangement is such that when the screw 71 is turned in one direction the slide 67 will move up on the stem 53 increasing the tension of the springs 69, and when turned in the other direction the slide 67 will move down on the stem 53, slackening the tension of the springs 69. This arrangement permits a proper adjustment of the resilient action under which the cleaning member 19 is urged against the window.

Means is also provided for moving the arm 18 outwards for disengaging the member 19 from the window, when this is desired. This is necessary when windows are cleaned which have the usual slats separating small panes of the window. The means includes a lever 75 formed from a U-shaped length of wire. The arms 75a of the lever 75 are pivotally mounted intermediate of their ends by a pintle 76 on the strip 32. The outer ends of the arms of the lever 75 are connected by a rod 77. A spring 78 is mounted between the rod 77 and a lug 79 upon the bottom of the strip 32. The arms of the lever 75 have their outer ends 75b turned laterally into loop portions. These loop portions 75b are engaged by the end of a cord or cable 80. This cord or cable 80 extends along the sides of the strip 32 and passes through eyelets 81 mounted on the sides of the strip 32.

The center of the cord or cable 80 is engaged by a hook 82 which is mounted upon the casing of a pulley 83. A cord or cable 84 engages over the pulley 83. This cord or cable 84 has one of its ends fixedly attached to an eye member 85 mounted on the strip 32. The other end of the cord or cable 84 slidably passes through an eye member 86, also mounted on the strip 32. A handle 87 is mounted upon the latter end of the cord 84. The arrangement is such that the handle 87 may be pulled to move the pulley 83 inwards and so move the cable or cord 80 inwards to move the outer ends of the arms of the lever 75, and pivot the lever 75 as indicated by the dot and dash lines 75' in Fig. 1. The lever 75 then strikes the arm 18 and is capable of pushing the arm 18 outwards so that the arm 18 pivots on the pintles 56 to a position in which the window cleaning member 19 will disengage from the window. When the handle 87 is released the parts will return to their original positions due to the contraction of the spring 78.

The operation of the device is as follows:

The frame 17 may be manually reciprocated inwards and outwards by gripping the handle 33 and moving it in the direction desired. The

springs 69 will maintain the arm 18 in a position in which the window cleaning member 19 maintains contact with the outside of the window pane being cleaned. Thus the member 19 will move upwards and downwards cleaning the outside of the window. The carriage 16 may be moved to a new lateral position on the window sill 13 to permit another vertical section of the window to be cleaned. The operation is continued until the entire outside of the sash of the window is cleaned. The cleaned sash is then moved out of the way and the other window sash is moved into a down position and may then be similarly cleaned. Whenever required the handle 87 may be pulled to indirectly cause the window cleaning member 19 to disengage from a window pane.

The carriage 16 may have its body sections 16' and 16" adjusted so that the flanges 29 of the rollers 22 engage edge portions or shoulders on the window sill 13, as shown in Fig. 1. Thus the carriage 16 may only be moved laterally and cannot possibly move upwards and rearwards on the window sill, except by accident. The hooks 21a prevent the carriage 16 from falling out of the window.

While I have illustrated and described my invention with some degree of particularity, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a window cleaning device having a carriage for resting upon and moving laterally on a window sill of a window, a frame slidably mounted on said carriage to be manually moved inwards and outwards of said window, an arm mounted on the outer end of said frame, a window cleaning member mounted on the outer end of said arm, and means for resiliently urging said arm towards said window for urging said member against said window during said inward and outward motion of said frame, and said means comprising a spring acting between said arm and said frame, and a slide adjustably mounted on one of these parts and connected with said spring for controlling the tension of said spring.

2. In a window cleaning device having a carriage for resting upon and moving laterally on a window sill of a window, a frame slidably mounted on said carriage to be manually moved inwards and outwards of said window, an arm mounted on the outer end of said frame, a window cleaning member mounted on the outer end of said arm, and means for resiliently urging said arm towards said window for urging said member against said window during said inward and outward motion of said frame, and said means including springs acting to urge said arm towards said window, said springs being mounted at one of their ends on said frame and at the other of their ends being connected with a slide on said arm, and means for holding said slide in various positions for tensioning said springs.

3. In a window cleaning device having a carriage for resting upon and moving laterally on a window sill of a window, a frame slidably mounted on said carriage to be manually moved inwards and outwards of said window, an arm

mounted on the outer end of said frame, a window cleaning member mounted on the outer end of said arm, and means for resiliently urging said arm towards said window for urging said member against said window during said inward and outward motion of said frame, said frame comprising a rigid strip, crossbars mounted upon said strip, and tracks mounted on said crossbars and slidably connected with said carriage, said tracks comprising track elements mounted between said crossbars.

4. In a window cleaning device having a carriage for resting upon and moving laterally on a window sill of a window, a frame slidably mounted on said carriage to be manually moved inwards and outwards of said window and having crossbars mounted on its inner and outer ends, an arm mounted on the outer end of said frame, a window cleaning member mounted on the outer end of said arm, and means for resiliently urging said arm towards said window for urging said member against said window during said inward and outward motion of said frame, and tracks mounted on said crossbars and slidably connected with said carriage, said tracks comprising wires mounted between said crossbars.

5. In a window cleaning device having a carriage for resting upon and moving laterally on a window sill of a window, a frame slidably mounted on said carriage to be manually moved inwards and outwards of said window, an arm mounted on the outer end of said frame, a window cleaning member mounted on the outer end of said arm, and means for resiliently urging said arm towards said window for urging said member against said window during said inward and outward motion of said frame, and tracks mounted on said crossbars and slidably connected with said carriage, said tracks comprising wires, and means for holding said wires in taut positions.

6. In a window cleaning device having a carriage for resting upon and moving laterally on a window sill of a window, a frame slidably mounted on said carriage to be manually moved inwards and outwards of said window, an arm mounted on the outer end of said frame, a window cleaning member mounted on the outer end of said arm, and means for resiliently urging said arm towards said window for urging said member against said window during said inward and outward motion of said frame, and tracks mounted on said crossbars and slidably connected with said carriage, said tracks comprising wires, and means for holding said wires in taut positions, comprising hooks connected with one of the ends of the wires, and means for holding said hooks in various longitudinally adjusted positions.

7. In a window cleaning device having a carriage for resting upon and moving laterally on a window sill of a window, a frame slidably mounted on said carriage to be manually moved inwards and outwards of said window, an arm

mounted on the outer end of said frame, a window cleaning member mounted on the outer end of said arm, means for resiliently urging said arm towards said window for urging said member against said window during said inward and outward motion of said frame, and means for moving said arm outwards for disengaging said member from said window and comprising a lever movably mounted on said frame, and means for moving said lever to strike and lift said arm.

8. In a window cleaning device having a carriage for resting upon and moving laterally on a window sill of a window, a frame slidably mounted on said carriage to be manually moved inwards and outwards of said window, an arm mounted on the outer end of said frame, a window cleaning member mounted on the outer end of said arm, means for resiliently urging said arm towards said window for urging said member against said window during said inward and outward motion of said frame, and means for moving said arm outwards for disengaging said member from said window, comprising a lever pivotally mounted on said frame and adapted in a pivoted position to strike and lift said arm, means for urging said lever into an inoperative position, and means for moving said lever.

9. In a window cleaning device having a carriage for resting upon and moving laterally on a window sill of a window, a frame slidably mounted on said carriage to be manually moved inwards and outwards of said window, an arm mounted on the outer end of said frame, a window cleaning member mounted on the outer end of said arm, means for resiliently urging said arm towards said window for urging said member against said window during said inward and outward motion of said frame, and means for moving said arm outwards for disengaging said member from said window, comprising a lever pivotally mounted on said frame and adapted in a pivoted position to strike and lift said arm, means for urging said lever into an inoperative position, and means for moving said lever, comprising a cord connected with said lever, a hook connected with said cord and mounted on a pulley, and another cord extended over said pulley and having one end stationarily mounted on said frame and its other end manually movable.

10. In a window cleaning device having a frame to be manually moved inwards and outwards of a window having a sill with stepped sections, a carriage for supporting said frame on the sill of said window, comprising an inner body section and an outer body section adjustably connected, flanged wheels mounted on said body sections for engaging the steps of said sill, and hooks for preventing said carriage from falling out of said window, the tops of said sections sloping downwards and outwards, and a protector for extending over said sill to protect said frame and comprising flexible strands depending from said carriage, and wooden rods closely spaced and mounted across said strands.

FREDERICK SUPNICK.
